UNITED STATES PATENT OFFICE.

ALLEN B. KENDALL, OF MAYWOOD, ILLINOIS, ASSIGNEE TO REGAN SAFETY DEVICES COMPANY, INC., A CORPORATION OF NEW YORK.

DIAPHRAGM RESERVOIR AND BRAKE VALVE.

Application filed February 7, 1921. Serial No. 443,046.

To all whom it may concern:

Be it known that I, ALLEN B. KENDALL, a citizen of United States, residing at Maywood, in the county of Cook and State of

Illinois, have invented certain new and useful Improvements in Diaphragm Reservoirs and Brake Valves, of which the following is a specification, reference being had thereto in the accompanying drawing.

10 This invention relates to improvements in a diaphragm reservoir and brake valve for use in connection with a train control system, the invention including a construction so designed as to be controlled so that the 15 electromagnet forming part of the train control system when energized permits the flow of air from the main reservoir to the engineer's brake valve, while the air brake venting valve is closed to prevent the venting of the same and the automatic application 20 of the brakes, the invention comprehending a construction including a diaphragm control of the reservoir and brake valve so that upon the deenergization of the 25 electromagnet the diaphragm is actuated for cutting off the engineer's brake valve from the main reservoir and for venting the air brake system to the atmosphere.

30 A further object of this invention is the provision of a novel form of diaphragm controlling valve in which a vacuum is created upon the operation of the valve in cutting off the engineer's brake valve from the main reservoir and in venting the air brake system to hold the valve in such position, the construction including two valve members mounted upon a single stem and controlled by two diaphragms, one of which is acted upon by the vacuum created.

40 In the accompanying drawings is illustrated a view partly in elevation and in section of the main working part of the valve, a portion only of the electromagnet being illustrated.

45 Referring to the drawings, the numeral 1 designates the lower member of the valve which is provided with the lower section 2 which as will later appear, cooperates with the lower section 4 of the intermediate casting 3, the sections being attached together by means of the bolts 5 for securing the diaphragm 21 in position. At the upper end of the casing 3 is also provided a reduced section of a diaphragm chamber which cooperates with the flange 8 of the upper sec-

tion 7, the upper end of said upper section being closed by the removable cap 9, which permits of the ready accessibility to the parts of the device.

The sections 2 and 4 provide the diaphragm chamber 10 while the section 3 with its concentric guiding sleeve 19 provides an intermediate chamber 11, the flanges 6 and 8 providing the upper diaphragm chamber 12, while the member 7 provides the two superposed chambers or compartments 13 and 14, which are in communication with each other through the valve seated port 17. Air is led from the main reservoir, not shown, through the T-coupling 15 and the nipple 16 into the chamber 14, where under normal conditions with the parts in the position as shown in the drawings, such air is admitted through the port 17 into the main chamber 13 and through the pipe 18 to the engineer's brake valve (not shown). Mounted in the guiding sleeve 19 is the valve stem 20, whose lower end is connected to the diaphragm 21, there being disposed above such diaphragm upon the reduced end of 80 said stem, a disk 22 carrying the valve 23 for controlling the annular port 24 at the lower end of the chamber 11. Further carried upon the stem 20 is diaphragm 25 while upon the extreme upper end is the disk 26 provided with disk valve 27 for controlling the valve seated port 17, as will, presently appear. Air is led from the air brake system through the pipe 28 into the chamber 11 and normally is prevented further egress 90 therefrom. When the valve 23 is unseated air is permitted to flow into chamber 10 and from thence through the vent openings or ports 29 to the atmosphere, thus venting the air brake system and bringing the train to 95 a halt.

In order to control the admission of air under pressure to the chamber 10 and consequently to control the position of the stem 20 with the various diaphragms and valves, there is provided an electromagnet 30, the stem 32 of which normally engages the cylindrical end 33 of the stem 33', which carries the lower valve 34 and the upper valve 35, the valve 34 being seated normally and the valve 35 being unseated when the electromagnet is energized, as illustrated. Air is led from the T-coupling 15 through the pipe 36 and strainer 37 into the duct or channel 38 to the chamber 39 through the chan-

nels 40, 41, and 42, into the chamber 10. Thus the pressure exerted will act upon the diaphragm 21 to hold the valves in the position as shown in the drawings, the valve 23 being closed and the valve 27 being open. Upon the deenergization of the magnet 30 and the consequent lowering of the stem 32, the stem 33' will fall, causing the valve 35 to close the escape from the chamber 39, but lowering the valve 34 so that the air in the chamber 10 will be vented through the channels 42 and 41, through the lower end of the channel 40 into the chamber 43 and to the atmosphere through the port 44. This releases the pressure from below the diaphragm 21. The valve 23 will be forced downwardly due to the pressure in the chamber 11 exerted upon the said valve 23, so that the air from the pipe 28 will enter the chamber 10' over the upper side of the diaphragm 21 and will be vented to the atmosphere through the ports 29, creating a vacuum in the chamber 12 with the result that the diaphragm 25 is drawn downwardly and thus assists in closing the port 17 and in opening the port 24, the valve members 27 and 23 controlling these ports being maintained in their corresponding positions by this action, the pressure medium flowing through the pipe 16 into the chamber 14 active on the disk 26 further assisting in holding the parts in this condition with the pipe 18 isolated from the pipe 16 and with the pipe 28 connected to the atmosphere.

35 The energization of the electromagnet causes the valves 34 and 35 to be again shifted, air being admitted to the under side of the diaphragm 21 into the chamber 10 forcing up the stem 20 and closing the valve 23, opening the valve 27, so the parts will assume their normal position as illustrated.

While I have shown my device in the preferred form, it will be obvious that many changes and modifications may be made in the structure disclosed without departing from the spirit of the invention, defined in the following claims.

What I claim as new is:

1. In a device of the class described, a main casing having a plurality of superposed inter-communicating chambers, a diaphragm controlled valve stem mounted concentrically of all the chambers, two valves carried by said stem and forming a controlling means between certain of said chambers, one of said valves being normally open and the other normally closed, a diaphragm mounted upon the lower end of the stem and secured to the casing, and an electro-magnetically controlled valve for effecting the introduction or escape of air relative to the diaphragm and for consequently effecting the movement of the valves.

2. In a device of the class described, a main casing having a plurality of super-

posed inter-communicating chambers, a diaphragm controlled valve stem mounted concentrically of all the chambers, two valves carried by said stem and forming a controlling means between certain of said chambers, one of said valves being normally open and the other normally closed, a diaphragm mounted upon the lower end of the stem, and electro-magnetically controlled valve for effecting the introduction or escape of air relative to the diaphragm and for consequently effecting the movement of the valves, and a second diaphragm carried by said stem and acted upon during the lowering action of the first diaphragm due to the venting of air to create a vacuum in assisting in the seating of the normally open valve and the opening of the normally closed valve.

3. A device of the character described, including a main casing having two pairs of chambers, said chambers being intercommunicating in pairs, two valves connected for movement in unison for controlling the intercommunication between said chambers, one valve normally being open and the other normally being closed, a diaphragm connected to control the movement of said valves, and electromagnetically operated means for controlling air pressure relatively to said diaphragm, the normally closed valve being arranged intermediate the diaphragm and the normally open valve.

4. A device of the character described, including a main casing having two pairs of chambers, said chambers being intercommunicating in pairs, two valves connected for movement in unison for controlling the intercommunication between such chambers, one valve normally being open and the other normally being closed, said casing being further provided with a diaphragm chamber and a diaphragm connected to said valve and mounted in said chamber, and electromagnetically operated means for controlling the induction and ejection of a pressure medium to such diaphragm chamber whereby said valves are operated, and a second diaphragm interposed between the two pairs of chambers and acted upon by the passage of air through one of said chambers for holding the normally open valve closed when the normally closed valve is open.

5. In a device of the class described, a member having two pairs of communicating chambers, two diaphragm chambers, one being below the lower pair and the other being between the two pairs of chambers, the latter being in communication with one of the chambers of the lower pair, a valve stem mounted concentrically of all of the chambers, two diaphragms, one connected at the extreme lower end and the other intermediate of said stems, two valves one connected at the lower end and the other at the extreme upper end of the stem for controlling the

- communication between the two respective pairs of chambers, and electromagnetically actuated valve means for controlling the supply and exhaust of a pressure medium 5 to the lower diaphragm whereby the movement of the stem is effected.
6. In a device of the class described, a casing having a plurality of chambers including two superposed chambers, a diaphragm controlled valve stem movable centrally of said superposed chambers, spaced valve members carried by said stem one for each of said superposed chambers, one of said valve members being normally open 10 and the other normally closed, and means for moving said valve members comprising a diaphragm secured to said stem and casing and provisions for controlling the flow of air to and from said diaphragm.
- 15 7. In a device of the class described, a casing having a plurality of chambers including two superposed chambers, a diaphragm controlled valve stem movable centrally of said superposed chambers, spaced valve members carried by said stem one for each of said superposed chambers, one of said valve members being normally open 20 and the other normally closed, and means for moving said valve members comprising a diaphragm secured to said stem and casing and provisions for controlling the flow of air to and from said diaphragm.
- 25 8. A reservoir and brake valve for a train system, comprising a casing, a port in said casing forming the communicating means between the main reservoir and the engineer's brake valve of the train system, a second port in said casing for forming the 30 communicating means between the air brake system and atmosphere, a valve stem movable in said casing, a plurality of spaced valve members on said valve stem, one for each of said ports, one of said valve members being normally open and the other normally closed, and means for moving said valve members comprising a diaphragm secured to said stem and casing and provisions for controlling the flow of air to and from said diaphragm.
- 35 9. A reservoir and brake valve for a train system, comprising a casing, a port in said casing forming the communicating means between the main reservoir and the engineer's brake valve of the train system, a second port in said casing for forming the 40 communicating means between the air brake system and atmosphere, a valve stem movable in said casing, a plurality of spaced valve members on said valve stem, one for each of said ports, one of said valve members being normally open and the other normally closed, and means for moving said valve members comprising a diaphragm secured to the valve stem and casing and provisions for controlling the flow of air to and from said diaphragm.
- 45 10. A reservoir and brake valve for a train system, comprising a casing, a port in said casing forming the communicating means between the main reservoir and the engineer's brake valve of the train system, a second port in said casing for forming the 45 communicating means between the air brake system and atmosphere, a valve stem movable in said casing, a plurality of spaced valve members on said valve stem, one for each of said ports, one of said valve members being normally open and the other normally closed, and means for moving said valve members comprising a diaphragm, a duct connected to said reservoir, and provisions for controlling the flow of air from said reservoir to said diaphragm for actuating the same, the said second port being arranged intermediate the first mentioned port and the diaphragm.
- 50 11. A reservoir and brake valve for a train system, comprising a casing, two spaced ports in said casing, two valves connected for movement in unison for opening and closing said ports, one valve being normally open and the other normally closed, a diaphragm connected to control the movement of said valves, the normally closed valve being arranged intermediate the diaphragm and the normally open valve and electromagnetically operated means for controlling the flow of a pressure medium relative to said diaphragm for actuating the same.
- 55 12. A reservoir and brake valve for a train system, comprising a casing, a port in said casing forming the communicating means between the main reservoir and the engineer's brake valve of the train system, a second port in said casing for forming the 60 communicating means between the air brake system and atmosphere, two valves connected for movement in unison for opening and closing said ports, one valve being normally open and the other normally closed, a diaphragm connected to control the movement of said valves, the said second port being arranged intermediate the first-mentioned port and the diaphragm and electromagnetically operated valve means for controlling the 65 flow of a pressure medium relative to said diaphragm for actuating the same.
- 65 13. A reservoir and brake valve for a train system, comprising a casing, a port in said casing forming the communicating means between the main reservoir and the engineer's brake valve of the train system, a second port in said casing for forming the 70 communicating means between the air brake system and atmosphere, two valves connect-

ed for movement in unison for opening and closing said ports, one valve being normally open and the other normally closed, a diaphragm connected to control the movement of said valves, electromagnetically operated valve means for controlling the flow of a pressure medium relative to said diaphragm for actuating the same, and a second dia-

phragm connected to affect the movement of said valves, said second diaphragm being arranged to be acted upon during the venting of the air brake system to create a vacuum in assisting the opening of one of the valves and the closing of the other. ¹⁰

In testimony whereof I affix my signature
ALLEN B. KENDALL.
